PIPE WRENCH

John R. Leonard, Washington, D. C.

Application October 8, 1947, Serial No. 778,590

4 Claims. (Cl. 81—179)

1

This invention relates to a pipe wrench.

One of the objects of the invention is to provide a pipe wrench which can get a fast grip on a pipe that lies close to a wall, without the necessity of any part of the wrench being interposed between the pipe and wall.

In the conventional pipe wrench the initial fast grip is obtained by rotating the wrench through an arc of considerable magnitude. When working with such a wrench upon a pipe which is close to the wall, the working arc may not be substantially greater than 180°, which arc is fully occupied by the jaws of the wrench when they are first placed astride the pipe so that there is no room for any turning movement of the wrench in order to get the initial hold on the pipe. Consequently, in such situations it is necessary to break away some of the plaster behind the pipe, so that one of the jaws can be placed back of the pipe, leaving some room at the front through which the wrench can be turned for gripping and turning the pipe.

The present invention provides a pipe wrench which takes up all lost motion upon being moved rectilinearly to an embracing position relative to the pipe, until it is in firm contact therewith, from which position a biting grip is immediately secured at the beginning of the turning movement, the major part of the turning movement being usefully employed in turning the pipe.

Another object of the invention is to provide a pipe wrench of the type described, the jaws of which are tapered toward their free ends forwardly of the normal turning center of the wrench, to increase the turning arc when working upon a pipe close to a surface which normally would obstruct the wrench.

A further object of the invention is to provide a pipe wrench as described, in which upon initial turning movement of the wrench in a tightening direction, the jaws tilt to positions of tangency to the pipe, forward of the normal diametrical points of tangency at which they engage the pipe prior to tightening movement, thereby reducing the width of the mouth of the wrench to less than the diameter of the pipe, so that the pipe is positively prevented from slipping forward in the jaws, ensuring immediate seizure of the pipe and maintenance of the grip until the wrench is reversely turned in a release direction.

Other objects of the invention will appear as the following description of a preferred and practical embodiment thereof proceeds.

In the drawings:

Figure 1 is a side sectional view of a wrench embodying the principles of the invention, in its initial position with respect to a pipe;

2

Figure 2 is a side elevation, partly in section, showing the pipe entered between the jaws, but not gripped;

Figure 3 is a similar view showing the pipe gripped;

Figure 4 is a cross-section taken along the line 4—4 of Figure 2;

Figure 5 is a cross-section taken along the line 5—5 of Figure 2;

10 Figure 6 is a cross-section taken along the line of Figure 2.

Referring now in detail to the several figures, the numeral 1 represents the body of the wrench having a handle 2 and an integral fixed jaw 3. Cooperating with the body 1 or fixed member, is the movable member 4 having a movable jaw 5 complementary to the fixed jaw 3, said movable jaw being integral with an adjusting stem 6, and being disposed substantially at right angles thereto. The handle 2 preferably extends in a direction perpendicular to the stem 6, that is, in a general direction opposite to the mouth of the wrench.

The stem 6 has a series of concave teeth 7 on its back face engageable with a worm 8, by means of which the width of the jaw opening is adjusted. The wrench is preferably made to take only two sizes of pipe, primarily to minimize the requisite length of the stem 6, so that the latter will not project unduly when adjusted for a small pipe, and secondarily to prevent the wrench from being used on a pipe too large for its strength and becoming broken through the use of an extension on its handle.

35 The stem 6 is slidable through a guide in the body 1. Said guide has two aligned portions 9 and 10, spaced apart. The upper portion 9 is a channel, open at the front. The lower portion 10 is a closed bore. The stem 6 is of uniform cross-section throughout the extent of its toothed portion, being provided with re-entrant side faces forming channels 11, which fit about projecting ribs 11' extending longitudinally of the inner sides of the guide channel 9 and the guide bore 10. The inner back walls of the guide portions 9 and 10 lie in the same plane and are slidably engaged by the toothed rear face of the stem 6.

40 The body 1 between the portions 9 and 10 of the stem guide terminates in the common transverse plane that embraces the open front of the guide channel 9 and the inner front face of the guide bore 10. It is formed with a recess 13, opening in its front face, wider than the width of said guide channel and guide bore, and extending depthwise, that is, in a direction toward the handle, a sufficient distance to house the worm 8 with freedom of the worm to rotate in said recess. Above the recess 13 the guide channel

9 has a narrow slot 14 extending depthwise, and below said recess 13 the guide bore has a similar slot 15, said slots opening into the recess 13. These slots are to receive the aligned trunnions 16 and 17 of the worm 8, and terminate at such a point as to position the worm with only its thread extending into the path of the teeth 7 of the stem 6. The body 1 has aligned openings 18, through its opposite sides, exposing the sides of the worm, giving access for its manipulation.

In assembling the wrench, in the first instance the worm is introduced from the front into the recess 13 with its trunnions in the slots 14 and 15, and pushed back until the trunnions engage the ends of said slots. This positions the worm with its thread extending into the path of the stem 6 of the movable member 4. Next, the stem 6 is introduced into the guide groove 9 and pushed down until its toothed back face contacts the thread of the worm. Then the worm is turned, screwing the stem 6 down until it enters the guide bore 10, passes therethrough, and projects from the lower end thereof. An end plate 19 is provided, having the same cross-sectional shape as the stem 6, but no thread teeth on its rear face, which is screwed congruently onto the projecting end of the stem 6, making the movable member inseparable from the fixed member. The body or fixed member 1 is of greater thickness than the diameter of the worm in those regions which surround the openings 18, so that the worm is below the plane of the sides of the fixed member and protected from being battered through misuse.

The jaws 3 and 5 are formed with curved inner faces 20 and 21, respectively, that of the upper jaw being concave and that of the lower jaw being convex. Toothed jaw members 22 and 23 having correspondingly curved outer faces, slide along the respective curved faces 20 and 21 of the upper and lower jaws, being retained and guided by dovetail tracks 24 and 25, formed on the respective jaws 5 and 3, slidably supported by complementary dovetail grooves on the respective jaw members 22 and 23. The tracks terminate short of the free ends of the jaw members, so that they will not become marred by chance contact with the work in the use of the wrench. The curvature of the interfaces between the jaws and jaw members extends in an upward direction throughout the range of sliding movement of the jaw members; that is, said grooves are struck from radii which lie beyond the range of travel of the jaw members in a direction toward the closed end of the mouth of the wrench. The toothed faces 26 and 27 are straight, the upper toothed face 26 being chordal with respect to the grooved face 20, while the lower toothed face is tangential with respect to the curved face 21. Consequently, the upper jaw member 22 tapers toward its outer end, said outer end being thin, while the jaw member 23 tapers towards its inner end, its outer end being thick. Both toothed faces in the course of operation of the wrench deviate slightly from a relation of mutual parallelism. As the jaw members 22 and 23 move inwardly upon the respective upwardly curved guide tracks, the toothed face of each tilts in a clockwise direction, and as said jaw members move outwardly, their toothed faces tilt counterclockwise.

The upper jaw member 22 is normally held in a neutral position by a spring 28, inserted in a bore in the slidable jaw and projected into the apex of a V-shaped notch in the upper jaw member. From this position, said jaw member can

move either inward or outward. When in neutral position, its outer end is slightly inward with respect to the outer end of the jaw 5, so that its thin end is protected and reinforced by the overhang of said jaw.

The lower jaw member 23 is normally held in its foremost position by means of a spring 29, mounted in a bore in the fixed jaw 3 and projecting into a notch in the lower jaw member. From this position the lower jaw member is yieldable inwardly. There is ample clearance between the inner ends of the jaw members and the adjacent structure which constitutes the closed end of the wrench mouth to permit the necessary range of sliding movement of the jaw members.

When in normal inactive position, as shown in Figure 1, the toothed face 26 of the upper jaw member 22 is inclined slightly downwardly toward the plane of the toothed face 27 of the lower jaw member 23. The lower jaw member normally projects outwardly beyond the upper jaw member, being complementary to the overhanging end of the movable jaw 5.

The wrench operates as follows: First, the mouth of the wrench is closed until its outer end is just too small to admit the pipe, as in Figure 1. Then the wrench is pressed against the pipe and pushed astride it by a rectilinear movement, the upper jaw being pressed radially toward the pipe to favor the movement of the upper jaw member preferentially to the lower jaw member. The first action is that the pipe pushes the upper jaw member back, causing it to ride up on its curved track. This widens the jaw mouth, since as the upper jaw member moves back, it also moves upwardly. Also, its toothed face tilts in a clockwise direction, admitting the pipe into the mouth of the wrench. The pipe may be introduced as far into the mouth as may be desired, at least until the diameter of the pipe is some little distance inwardly of the end of the upper jaw member 22, as shown in Figure 2. There will never be a space between the pipe and jaw members, for the upper jaw member constantly thrusts forwardly in a wedge-like manner, automatically taking up any looseness between the jaw members and pipe.

Due to the fact that the lower jaw member projects beyond the upper jaw member, the point of tangency of the pipe with the toothed face 27 is quite a distance inwardly from the end of the lower jaw member.

Up to this time, no turning movement has been imparted to the wrench, but the toothed faces of both jaw members are in firm contact with the pipe, due to the automatic outwardly directed wedging action of the upper jaw member. Now the wrench is turned in a clockwise direction. The immediate result of this movement is to force the upper jaw member outwardly and the lower jaw member inwardly. Since the upper jaw member moves down-hill when moving outwardly, while the lower jaw member moves up-hill in moving inwardly, the toothed faces 26 and 27 of the respective jaw members will move towards one another, forcibly embedding their teeth more or less into the pipe according to its hardness, to obtain a biting grip. In moving down-hill, the free end of the upper jaw member tilts downward, while in moving up-hill, the free end of the lower jaw member tilts upward. This mutual convergence of the jaws narrows the mouth of the wrench to a width less than the diameter of the pipe, as shown in Figure 3, and prevents the pipe from slipping from the jaws, even though the toothed faces may be somewhat worn or

clogged. The fact that the wrench cannot escape from the pipe eliminates a danger hazard, particularly when working on an overhead pipe.

Upon release of the wrench, the upper jaw member is urged inward, while the lower jaw member is urged outward, the biting grip upon the pipe being released so that the wrench turns freely about the pipe, but the upper jaw member is constantly biased wedgingly outward by the spring 23, so that both jaw members are maintained in firm contact with the wrench during its reverse movement, enabling the wrench to immediately pick up its biting grip when it is pulled in a clockwise direction.

While I have in the above description disclosed what I believe to be a preferred and practical embodiment of the invention, it will be understood by those skilled in the art that the specific details of construction and arrangement of parts, as shown, are by way of example and not to be construed as limiting the scope of the invention.

What I claim as my invention is:

1. Pipe wrench having upper and lower jaws defining the mouth of the wrench, the confronting faces of said jaws being upwardly curved in a direction from their free ends towards the closed end of the wrench mouth, the curvature of the upper jaw being concave and that of the lower jaw being convex, longitudinal track means on said curved faces, upper and lower jaw members having complementary curved faces engaging the curved faces of said jaws, longitudinally slidable thereupon and retained by said track means, the opposite faces of said jaw members being planiform and toothed and so disposed with respect to the respective curved faces as to mutually converge toward their forward ends when the upper jaw member is in a forward position and the lower jaw member in a rear position, and being mutually slightly divergent toward their forward ends when both are in their forward positions.

2. Pipe wrench having upper and lower jaws defining the mouth of the wrench, the confronting faces of said jaws being upwardly curved in a direction from their free ends toward the closed end of the wrench mouth, the curvature of the upper jaw being concave and that of the lower jaw being convex, longitudinal track means on said curved faces, upper and lower jaw members having complementary curved faces engaging the curved faces of said jaws, longitudinally slidable thereupon and retained by said track means, the opposite faces of said jaw members being planiform and toothed and so disposed with respect to the respective curved faces as to mutually converge toward their free ends when the upper jaw member is in a forward position and the lower jaw member is in a rear position, and being mutually slightly divergent toward their free ends when both are in their forward positions, a spring yieldably holding said upper jaw member in a neutral position from which it can move forward or rearwardly, and a spring yieldably holding said lower jaw member in its foremost position.

3. Pipe wrench having upper and lower jaws defining the mouth of the wrench, the confronting faces of said jaws being upwardly curved in a direction from their free ends towards the closed end of the wrench mouth, the curvature of the upper jaw being concave and that of the lower jaw being convex, longitudinal track means on said curved faces, upper and lower jaw members having complementary curved faces engag-

ing the curved faces of said jaws, longitudinally slidable thereupon and retained by said track means, the opposite faces of said jaw members being planiform and toothed and so disposed with respect to the respective curved faces as to mutually converge toward their free ends when the upper jaw member is in a forward position and the lower jaw member is in a rear position, and being mutually slightly divergent toward their free ends when both are in their forward positions, a spring yieldably holding said upper jaw member in a neutral position from which it can move forward or rearwardly, and a spring yieldably holding said lower jaw member in its foremost position, said jaws being each externally convergent toward its free end, the forward end of said upper jaw member being thin and when in foremost position being overhung by the free end of said upper jaw, the forward end of said lower jaw member being thick and when in foremost position extending beyond the free end of said lower jaw.

4. Pipe wrench comprising a fixed member including a lower jaw, and a cooperating movable member adjustable with respect to said fixed member and including an upper jaw, said jaws defining the mouth of the wrench, the confronting faces of said jaws being upwardly curved in a direction from their free ends toward the closed end of the wrench mouth, the curvature of the upper jaw being concave and that of the lower jaw being convex, longitudinal track means on said curved faces, upper and lower jaw members having complementary curved faces engaging the curved faces of said jaws, longitudinally slidable thereupon and retained by said track means, the opposite faces of said jaw members being planiform and toothed, and so disposed with respect to the respective curved faces as to mutually converge toward their free ends when the upper jaw member is in forward position and the lower jaw member in a rear position, and being mutually slightly divergent toward their free ends when both are in their forward positions, a spring yieldably holding said upper jaw member in a neutral position from which it can move forward or rearward and a spring yieldably holding said lower jaw member in its foremost position, said jaws being each externally convergent toward its free end, the forward end of said upper jaw member being thin and when in foremost position being overhung by the free end of said upper jaw, the forward end of said lower jaw member being thick, and when in its foremost position extending beyond the free end of said lower jaw.
